CLAIM

The ornamental design for a packing member for partitioning a carrying case, as shown and described.

DESCRIPTION

FIG. 1 is a perspective view of a packing member for partitioning a carrying case showing my new design;

FIG. 2 is a front elevational view thereof;

FIG. 3 is a front elevational view thereof in a partially separated position;

FIG. 4 is a top plan view thereof in a flattened position;

FIG. 5 is a right side elevational view thereof of FIG. 4, the left side being a mirror image;

FIG. 6 is a front elevational view thereof of FIG. 4;

FIG. 7 is a bottom plan view thereof of FIG. 4.

FIG. 1FIG. 2FIG. 3FIG. 4FIG. 5

FIG. 6

FIG. 7
